US00D832233S

(12) **United States Design Patent** (10) **Patent No.:** **US D832,233 S**
Brunner et al. (45) **Date of Patent:** **** Oct. 30, 2018**

(54) **AUDIO LISTENING SYSTEM**(71) Applicant: **Apple Inc.**, Cupertino, CA (US)(72) Inventors: **Robert Brunner**, San Francisco, CA (US); **Gregoire Vandenbussche**, San Francisco, CA (US); **Christopher Fruhauf**, San Anselmo, CA (US)(73) Assignee: **Apple Inc.**, Cupertino, CA (US)(**) Term: **15 Years**(21) Appl. No.: **29/593,122**(22) Filed: **Feb. 6, 2017****Related U.S. Application Data**

(60) Continuation of application No. 29/526,277, filed on May 7, 2015, now Pat. No. Des. 778,255, which is a continuation of application No. 29/488,470, filed on Apr. 18, 2014, now Pat. No. Des. 729,198, which is a division of application No. 29/475,634, filed on Dec. 4, 2013, now Pat. No. Des. 704,163, which is a continuation of application No. 29/417,832, filed on Apr. 9, 2012, now Pat. No. Des. 696,226, which is a division of application No. 29/382,418, filed on Jan. 3, 2011, now Pat. No. Des. 657,345.

(57) **CLAIM**

The ornamental design for an audio listening system, as shown and described.

DESCRIPTION

FIG. 1 is a front perspective view of an audio listening system showing the claimed design;

FIG. 2 is a front view thereof;

FIG. 3 is a right side view thereof;

FIG. 4 is a left side view thereof;

FIG. 5 is a rear view thereof;

FIG. 6 is a top view thereof; and,

FIG. 7 is a bottom view thereof.

The broken lines in the figures show portions of the audio listening system that form no part of the claimed design.

1 Claim, 4 Drawing Sheets
